TOY WHISTLE

Louis J. Sofro, Pawtucket, R. I., assignor to Reliance Molded Plastics, Inc., Pawtucket, R. I., a corporation of Rhode Island

Application July 17, 1950, Serial No. 11,224

Term of patent 3½ years

(Cl. D34—15)

To all whom it may concern:

Be it known that I, Louis J. Sofro, a citizen of the United States, residing in Pawtucket, in the county of Providence and State of Rhode Island, have invented a new, original, and ornamental Design for a Toy Whistle, of which the following is a specification, reference being had to the accompanying drawing, forming part thereof.

The single drawing figure is a top perspective view of a toy whistle showing my new design; the bottom of the device being similar.

I claim:

The ornamental design for a toy whistle, as shown and described.

LOUIS J. SOFRO.
